UNITED STATES PATENT OFFICE.

WILLIAM F. FOLMER, OF BROOKLYN, NEW YORK.

ILLUMINATING APPARATUS.

SPECIFICATION forming part of Letters Patent No. 397,903, dated February 19, 1889.

Application filed November 17, 1887. Serial No. 255,419. (No model.)

To all whom it may concern:

Be it known that I, WILLIAM F. FOLMER, of Brooklyn, in the county of Kings and State of New York, have invented a certain new and 5 useful Improvement in Gas-Cocks, of which the following is a specification.

I will describe a gas-cock embodying my improvement, and then point out the novel features in the claims.

10 In the accompanying drawings, Figure 1 is a sectional view of a gas-cock and its connections embodying my improvement. Fig. 2 is a horizontal section of the cock which is included in Fig. 3. Fig. 3 is a horizontal section of a cock of similar construction, but modified to adapt it for controlling a different number of burners.

Similar letters of reference designate corresponding parts in all the figures.

20 L designates a gas-supply pipe. At the lower end of the pipe any desirable number of burners M may be arranged. These burners may all be controlled by a cock, N. The plug of the cock N, I have shown as provided 25 with a circular wheel-like hand-piece, N', and with a flat piece, N², which may be grasped by the jaws of any desirable lighter or other device for the purpose of turning the plug of the cock.

30 The cock N is somewhat peculiar. Its principle of construction is such that it may be used with two burners or with any greater number of burners. I will first explain it with reference to Fig. 2, where it will be seen 35 that the arms or pipes extending to the gas-burners from the shell of the cock are four in number, equidistant and radial. The plug of the cock has a vertical central opening which communicates directly with the gas-

40 pipe L, and is provided with two side ports, n, which are diametrically opposite to each other, and two narrower ports, n', which are also opposite to each other. The narrow ports n' are of about the capacity of the arms or pipes 45 extending to the burners; but the wider ports are about twice as wide as the arms or pipes extending to the burners which they control. Consequently it is possible to so turn the cock that all four ports will permit gas to flow 50 to the burners. This is illustrated in Fig. 3. If the plug of the cock should be turned in

the direction indicated by the arrow in Fig. 2 only far enough to move the ports n' out of line with the burner arms or pipes designed to be supplied from such ports, then these 55 burner arms or pipes will be cut off, and still the ports n will remain operative to conduct gas to their burner arms or pipes. The plug of the cock may be turned still farther in the direction of the arrow to move the ports n, as 60 well as the ports n', out of line with the burner arms or pipes.

In the modification of the cock which I have shown in Fig. 3 there are but three ports, intended to control three burner arms or pipes. 65 The port n is about twice as wide as the burner arm or pipe with which it coacts. The ports n' are about the same size as the burner arms or pipes with which they coact. Consequently the cock may be turned in the direction indicated by the arrow adjacent to Fig. 3, to cut off the burner arms or pipes with which the ports n' coact and to leave the port n in condition to supply gas to its burner arm or pipe, and may be turned still farther in the 75 direction of the arrow to render the port n inoperative to supply gas to its burner arm or support. If the plug of the cock shown in Fig. 2 or of the cock shown in Fig. 3 should be moved in the reverse direction to the arrows, all the ports could be rendered inoperative, or the flame of all the burners may be lowered to any desired point. 80

The shell of the cock is shown as provided with stop-pins n² n³, and the hand-piece N', 85 attached to the plug of the cock, is shown as provided with a pin or projection, n⁴. By these stops the plug of the cock may be limited as to its extreme positions of movement.

It will be seen that in the lower end of the 90 shell N of the cock a screw plug or nut, N³, is inserted. The upper end of this screw-plug bears against the lower end of the plug of the gas-cock. The plug of the gas-cock is made longitudinally tapering, so that by adjusting the screw-plug N³ the plug of the gas-cock may be forced upwardly within the shell N, to compensate for wear or looseness occasioned in any other manner. 95

The stop-pin n³ is shown as made in the 100 form of a screw and as passing through the portion of the shell N in which it fits and im-

pinging against the screw-plug N³. It therefore serves the purpose of a lock for the screw-plug.

What I claim as my invention, and desire 5 to secure by Letters Patent, is—

1. In combination with the supply-pipe, the burners, and the shell, the plug having the central vertical recess communicating directly with the supply-pipe, opposite ports of 10 a capacity equal to the burner-pipes, and a port between the opposite ports of a greater capacity than the burner-pipe, whereby the two opposite ports may be turned out of communication with their burner-pipes, and the 15 wider port having communication with its burner-pipe, substantially as specified.

2. In combination with the supply-pipe, the burners, and the shell, the plug provided with a central vertical recess communicating directly with the supply-pipe, the opposite ports having a capacity equal to the burner-pipes, the intermediate opposite ports having a greater capacity, whereby two or more alternate burner-pipes may be supplied with gas, 20 or all of the burner-pipes may be supplied, 25 substantially as specified.

3. The combination, with the shell and the plug having the hand-piece provided with a pin or projection, of the hollow screw-plug in the lower end of the shell, securing the plug 30 in place, and the stop-screw passing through a portion of the shell and impinging against the screw-plug and locking the same, substantially as specified.

4. The combination, with the supply-pipe, 35 the burner-pipes, and the shell, of the hollow plug having ports equal to the capacity of the burner-pipes and intermediate ports of a greater capacity than the first-named ports, whereby one or more ports may be turned 40 out of communication with their burner-pipes, leaving others in full communication when the plug is turned in one direction, and whereby all of the burner-pipes may receive a full or a reduced supply of gas, substantially as 45 specified.

WILLIAM F. FOLMER.
